UNITED STATES PATENT OFFICE.

JOHN N. SCISM, OF SYRACUSE, NEW YORK.

OUTLET-BOX.

No. 920,401.

Specification of Letters Patent.

Patented May 4, 1909.

Application filed February 12, 1908. Serial No. 415,615.

To all whom it may concern:

Be it known that I, JOHN N. SCISM, citizen of the United States, and resident of Syracuse, in the county of Onondaga, in the State of 5 New York, have invented new and useful Improvements in Outlet-Boxes, of which the following, taken in connection with the accompanying drawings, is a full, clear, and exact description.

- 10 The object of this invention is to provide an outlet-box which shall be simple and inexpensive in construction and adapted to contain electric fixtures of various kinds and varying sizes and securely sustain the fixture 15 in its required position. And to that end the invention consists in the novel construction and combination of the component parts of the outlet-box and means for sustaining the fixture therein as hereinafter described.
- 20 In the accompanying drawings, Figure 1 is a vertical transverse section of an outlet-box embodying my invention; Fig. 2 is a top or front view of the box, with the cover and snap-switch or fixture removed; Fig. 3 is a 25 vertical transverse section partly in elevation illustrating a modification of the clamping means; and Fig. 4 is a detached plan view of the diaphragm which is employed in the modified form of clamp.
- 30 Like numerals of reference indicate like parts in the several views.

—1— denotes the box which is composed of metal and may be of any suitable style. Said box is preferably of annular shape as 35 commonly used for the purpose stated and is provided at diametrically opposite sides with openings —2— for the entrance and exit of the electric-wires (not shown). In these openings are usually secured short tubes 40 —3— (indicated by dotted lines) through which the wires pass. If desired these tubes may be formed integral with the box; however they are generally fastened by correspondingly threading the openings and tubes.

45 The box is provided with an outwardly deflected cover —4— formed with a flat peripheral portion —5— which is seated on the box. Said peripheral portion —5— of the cover is provided with a series of apertures —6— which coincide with screw-threaded apertures —7— provided in inwardly projecting lugs —8— formed on the box, and in said apertures are inserted screws —9— for securing the cover in 50 position as shown in Fig. 1. The said cover —4— is provided with a larger central aper-

ture —10— for the protrusion of a portion of the electric-fixture, which may be of any suitable and well known form used in the installation of lighting and other electrical 60 systems.

For illustration in the present instance, the fixture consists of a so-called "snap-switch" as represented at —11—, the said fixture being provided with the usual block 65 or base —12— of insulating material in which are secured the electric-terminals (not necessary to be shown) to which the wires are to be connected.

The means of securing the fixture within 70 the box —1— comprises essentially an adjustably supported diaphragm —13— on which the fixture is seated and which serves to clamp the said fixture firmly against the cover —4—. The said diaphragm —13— 75 may be of any suitable and convenient shape, however it consists preferably of a flat ring which is provided with a series of screw-threaded apertures —14— for the reception of screws —15— which operate to 80 adjust the diaphragm —13 in relation to the cover —4— so as to cause the plate to exert the proper degree of pressure on the back of the fixture and thereby securely clamp the fixture between the diaphragm and cover. 85

The foregoing description sets forth the essential features of my invention, viz. an outlet-box provided with a diaphragm adjustable to different planes within said box and supporting the electric fixture, and 90 means for forcing said diaphragm toward the cover of the box to bind the said fixture between the diaphragm and said cover. This is clearly illustrated in both Figs. 1 and 3 of the drawings, with slight modifications of the 95 means for forcing the diaphragm toward the cover of the box.

In Fig. 1 the screws —15— extend from the diaphragm toward the bottom of the box and are supported thereon by means of spiral 100 springs —16— interposed between said bottom and nuts —17— applied to the screws, the fixture being thus cushioned in the box. The pressure of the diaphragm toward the 105 cover of the box can in this case be adjusted by turning either the screws —15— or the nuts —17—.

Referring to Fig. 3 of the drawings, it will be understood that the cover —4— may be secured to the box —1— by any suitable 110 means, preferably in the manner illustrated in Fig. 1 and hereinbefore described. In this

modified construction, the adjusting screws —15—15— pass through plain apertures —18—18— in the cover —4— and work in the correspondingly screw-threaded apertures —14—14— in the diaphragm —13— as before stated.

To guard against turning of the fixture —11—, I provide two or more screws —19—19— passing through the insulating block or base —12— thereof and engaging threaded apertures —20—20— in the diaphragm —13—; however, any other suitable means may be employed for the purpose. These apertures —20—20— are preferably provided in inwardly projecting lugs —21—21— formed on the inner peripheral edge of the ring or diaphragm —13— as shown more clearly in Fig. 4.

If desired the diaphragm —13— may be formed with a bar —22— extending diametrically across the same as indicated by dotted lines in Fig. 4.

It is obvious that in either of the described structures the parts can be quickly and easily assembled.

I prefer to cut out portions of the diaphragm —13—, at its outer peripheral edge as indicated at —13^X—13^X—, so as to accommodate the lugs —8—8— on the box, and permit the diaphragm —13— to be readily placed in the box or removed therefrom when desired.

What I claim as my invention is:

An outlet-box provided with a diaphragm adjustable to different planes within said box and supporting the electric-fixture, and means for forcing said diaphragm toward the cover of the box to bind the said fixture between the diaphragm and said cover.

JOHN N. SCISM.

In presence of—

J. D. FEELEY,
G. KAISER.
